US0D1028250S

(12) **United States Design Patent** (10) **Patent No.:** **US D1,028,250 S**
(45) **Date of Patent:** **** May 21, 2024**

(54) **VIEWER OF A PHYSICIAN CONSOLE**

(71) Applicant: **Auris Health, Inc.**, Redwood City, CA (US)

(72) Inventors: **Thomas G. T. Brisebras**, San Francisco, CA (US); **Juan B. Bajana Merizalde**, San Francisco, CA (US); **Fabien Y. Schmitt**, Redwood City, CA (US); **Christian de Jesus Ruiz**, Redwood City, CA (US); **Andrew Martin Torrance**, Redwood City, CA (US); **Travis C. Covington**, Campbell, CA (US); **Taylor R. Nicholson**, San Francisco, CA (US); **Colin Allen Wilson**, Burlingame, CA (US)

(73) Assignee: **Auris Health, Inc.**, Redwood City, CA (US)

(**) Term: **15 Years**

(21) Appl. No.: **29/759,098**

(22) Filed: **Nov. 19, 2020**

(51) LOC (14) Cl. **24-02**

(52) U.S. Cl.

USPC **D24/185**

(57) **CLAIM**

The ornamental design for a viewer of a physician console, as shown and described.

DESCRIPTION

FIG. 1 is a front perspective view of a viewer of a physician console, showing the new design;

FIG. 2 is a front view thereof;

FIG. 3 is a rear view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front perspective view thereof, shown in a position of use with a physician console drawn in broken lines.

The broken lines in the drawings in FIGS. 1-7 depict portions of the viewer of a physician console that form no part of the claimed design. The broken lines in FIG. 8 illustrating a physician console depict environment and form no part of the claimed design.

1 Claim, 8 Drawing Sheets
